BERNARD D. WILLIS, OF OAK PARK, AND ARTHUR J. RAY, OF CHICAGO, ILLINOIS, ASSIGNORS TO AUTOMATIC ELECTRIC COMPANY, OF CHICAGO, ILLINOIS, A CORPORATION OF ILLINOIS.

AUTOMATIC TELEPHONE SYSTEM.

Application filed November 29, 1920. Serial No. 427,177.

To all whom it may concern:

Be it known that we, BERNARD D. WILLIS and ARTHUR J. RAY, both citizens of the United States of America, and residents of 5 Oak Park, Cook County, Illinois, and Chicago, Cook County, Illinois, respectively, have invented certain new and useful Improvements in Automatic Telephone Systems, of which the following is a specification.

The present invention relates in general to automatic telephone systems, but more particularly to such automatic systems as include rural party lines; and the object 15 of the invention, briefly stated, is the provision of new and improved means for signalling the subscribers on rural lines.

More specifically, the invention provides a system of code ringing whereby a large 20 number of subscribers on a rural line may be selectively signalled in accordance with pre-assigned codes, and the principal feature is concerned with means for preventing false signals which might otherwise be 25 produced either by the calling subscriber hanging up or by the called party answering during the transmission of a code signal.

This feature and other improvements related thereto will be described fully herein-after, reference being had to the accompanying drawings.

In the drawings, comprising Figs. 1, 2, and 3, there is shown by means of the usual 35 circuit diagrams sufficient of the apparatus of an automatic telephone system to enable the invention to be readily understood. For convenience, a calling station A is shown in Fig. 1, and a called station A', in Fig. 2, the latter station being one of the stations 40 on a rural line, together with the exchange switching equipment required to connect the two stations. This equipment comprises the line switch C, individual to the line of station A, the selector D, and the connector H.

The line switch C is of the well known 45 rotary type, in which the wipers move in a forward direction only and have no normal position. Other types of line switch may be used, however, such as the plunger type, for example.

The selector D and connector H are 55 mechanically of the well known Strowger vertical and rotary type such as is in common use in many automatic exchanges at the

present time. Ordinary two wire circuits are used, which are shown in full and will be described.

In Fig. 3 is shown a code selecting switch which is indicated by the reference character F. This switch is also of the Strowger type, similar to the selector D and connector H. It has radically different circuits, however, which will be explained fully.

The reference character E indicates a code 65 ringing switch which cooperates with the code selecting switch F. The switch E is a simple rotary switch comprising the two wipers 236 and 237 with their associated banks, and a stepping magnet 214. Both 70 switches E and F are individual to the connector H.

A relay interrupter is shown just to the left of the switch E, where it is indicated by reference character I. This interrupter 75 may be common to the exchange, or to a group of connectors.

Having described the apparatus briefly, its operation may now be explained more in detail. For this purpose let it be assumed that the subscriber at substation A desires to call the subscriber at substation A' on the rural or party line X. Let it be further assumed that the number of party line X is 123 and that the code call for substation A' is 45. In this case the calling subscriber must dial the number 12345.

When the receiver is removed at the calling substation a circuit is completed over the conductors 11 and 12 for the line relay 90 15 of the line switch C. Upon energizing, relay 15 closes a circuit at its armature 20 which includes the winding of the switching relay 14 and the stepping magnet 16 in series, and at its armature 21 connects test 95 wiper 26 to the above circuit at a point midway between the switching relay and the stepping magnet. The operation now depends upon whether the trunk line with which the line switch wipers are associated 100 is busy or idle. If the trunk line is busy there is a ground potential upon the test contact 29 with which the test wiper 26 is in engagement; the switching relay 14 is short circuited and the stepping magnet 16, 105 which interrupts its own circuit, is operated in the manner of a buzzer to advance the switch wipers in search of an idle trunk line. However, we may assume in the present case that when the call is initiated the 110

trunk line upon which the wipers of the line switch are standing is idle. Under these circumstances when the line relay 15 is energized the switching relay 14 is not short circuited and the stepping magnet 16 is not operated because of the high resistance of said switching relay. The latter relay, however, is energized, grounds the test wiper 26 at its armature 18, and at its 10 armatures 17 and 19 disconnects the line conductors 11 and 12 from the windings of relay 15 and from ground, respectively, and extends them by way of wipers 25 and 27, and bank contacts 28 and 30, to the line relay 31 of the first selector D. The line relay 31 and the release relay 32 of the selector D are now energized in the usual manner and the latter relay grounds the release trunk conductor leading to test contact 29 of the trunk line in order to establish a holding circuit for the switching relay 14 of the line switch C. This operation is well understood and need not be explained further.

35 The calling subscriber may now operate his calling device in accordance with the first digit 1 of the desired number. When the line circuit is interrupted by the calling device the line relay 31 falls back and closes the circuit of the vertical magnet 33 in series with slow acting relay 34. The vertical magnet operates to raise the switch shaft and wipers to the desired level. Relay 34 is energized in series with the vertical magnet 33 and, as soon as the vertical off normal springs 39 are closed, operates the stepping relay 35 over the following circuit: From ground through the working contact of armature 51 and the said armature, armature 53 and its working contact, off normal springs 39, and through the stepping relay 35 to battery. When relay 35 energizes over the above traced circuit it prepares the rotary magnet circuit at armature 55 and at armature 54 it locks itself to ground in series with the interrupter contacts 75 of the rotary magnet 40. When the slow acting relay 34 falls back after the end of the vertical impulses a circuit is closed for the rotary magnet 40 as follows: from ground through the working contact of armature 51 and the said armature, armature 53 and its resting contact, armature 55 and its working contact, and through rotary magnet 40 to battery. The rotary magnet energizes over this circuit and rotates the wipers onto the first set of contacts in the level opposite which they were raised, and also interrupts the circuit of the stepping relay 35 allowing it to fall back and break the circuit of the rotary magnet which deenergizes and closes its interrupter contacts again. The operation now depends upon whether the trunk connected to the first set of contacts is busy 60 or idle. If the trunk is busy ground is

present on the test contact, and a circuit for the stepping relay 35 is closed allowing it to energize again to operate the rotary magnet 40 to step the wipers over to the next set of contacts. This operation continues until an idle trunk is found.

When an idle trunk is found, which we will assume is the trunk line shown in the drawing, the switching relay 36, being no longer short circuited, energizes over the following circuit: from ground through the working contact of armature 51 and the said armature, switching relay 36, interrupter contacts 75 of rotary magnet 40, off normal springs 39, and through stepping relay 35 to battery. Relay 35, however, being wound with relatively few turns, does not energize in series with relay 36. When relay 36 energizes it extends the calling line by way of wipers 61 and 63, contacts 64 and 66, and conductors 67 and 69, to the line relay 100 of the connector H. The line and release relays 100 and 101 of the connector H accordingly energize and the latter grounds release trunk conductor 68, thus holding the selector D and the line switch C in their respective operated positions, and prepares a circuit for the vertical magnet 102.

30 The calling subscriber may now operate his calling device in accordance with the second digit 2 of the desired number. At each interruption at the calling device the line relay 100 falls back and operates the vertical magnet 102 in series with relay 103, raising the switch shaft and wipers to the second level. Slow acting relay 103 is accordingly energized, and, in conjunction with the switching of the vertical off normal springs on the first vertical step, shifts the path of the impulses from the armature 120' of the line relay 100 so that they come through armature 124 and its working contact. When the slow acting relay 103 de-energizes after the series of vertical impulses the impulsive circuit is shifted from the vertical magnet 102 to the rotary magnet 110.

35 In response to the calling of the third digit 3 of the called number, the rotary magnet 110 rotates the wipers 141-143, inclusive, into engagement with contacts 144-146, inclusive. Slow acting relay 114 is energized in multiple with the rotary magnet and remains energized during the entire operation. The operation now depends upon whether the called line is busy or idle. If it is busy ground is present on test contact 145 and busy test relay 118 energizes over the following circuit: from grounded contact 145 through wiper 142, armature 115 and its working contact, armature 134 and its resting contact, and relay 118 to battery. When the slow acting relay 114 falls back, said relay 118 remains locked up over a circuit

that includes its armature 130. The test relay 118 also opens the rotary magnet circuit at armature 111 in order to prevent further rotation of the wipers in case the calling dial is again manipulated, and at armature 119 completes a connection from the busy signalling machine to the lower line conductor. This operation gives the calling subscriber an audible busy signal to inform him that the called line is busy, and he will hear the signal and replace his receiver.

Let us assume, however, that the called line is idle when the connector H is operated, as before explained, to establish connection therewith. Under these circumstances as soon as the slow acting relay 114 deenergizes upon the cessation of the rotary movement, the following circuit is completed: from ground through the working contact of armature 120 and said armature, armature 130 and its resting contact, upper winding of relay 117, resting contact of armature 115 and the said armature, test wiper 142, test contact 145, switching relay 160 of the calling switch and through the stepping magnet 162 to battery. Relays 117 and 160 energize over the above traced circuit. Relay 160, upon energizing, removes the line relay bridge at the line switch C', while relay 117 locks itself to ground, completes at armatures 133 and 137 the connection to the line wipers 141 and 143, and closes a circuit for relay 116 which operates to shift the operating circuit to conductor 176 leading to the frequency selector F.

In response to the fourth digit 4 of the called number the vertical magnet 201 of the frequency selector F receives four impulses over operating conductor 176. The first impulse comes through vertical off normal springs 211 and 209, slow acting relay 202 and vertical magnet 201 to battery. Upon the first vertical step the off normal springs operate and relay 202 energizes and completes a new path for the impulses as follows: from conductor 176 through off normal springs 211 and 210, armature 238 and its working contact, relay 202, and vertical magnet 201 to battery. The vertical magnet and the slow relay 202 receive three more impulses over the new circuit which steps the switch shaft and wipers up until they stand opposite the fourth level of bank contacts. Soon after the last vertical impulse the slow acting relay 202 deenergizes and when it does so it switches the impulsive circuit to the rotary magnet 203 over the following path: armature 238 and its resting contact, armature 227 and its resting contact, slow acting relay 204 and through rotary magnet 203 to battery.

The calling subscriber may now operate his calling device in accordance with the last digit 5 of the desired number. A series of impulses, as before, come over the operat-

ing circuit. In response to these impulses the rotary magnet operates to step the wipers 234 and 235 into engagement with the fifth set of contacts in the fourth level, opposite which they were previously raised. Relay 204 is energized in series with the rotary magnet 203 and at armature 225 closes a circuit for relay 205 which energizes and locks itself to conductor 173 and thence through the resting contact of armature 128 and said armature, armature 123 and its working contact to ground. At armature 227 relay 205 opens the circuit for the rotary magnet; however, relay 204 at armature 224 previously closed a multiple circuit so that the rotary magnet circuit is held closed until the end of the last impulse when it is opened by the falling back of relay 204, which prevents further rotation of the wipers in case the calling subscriber should again operate his calling device. Relay 205, upon energizing, also closes at armature 223 a circuit for the interrupter I. Relays 261, 262, and 263 receive a momentary impulse. Relay 261, being of the ordinary quick acting type, falls back first and closes again the circuit for relay 263. Relay 263 remains energized for a time and holds the circuit to relay 262 open. Relay 262, upon deenergizing, closes again the circuit for relay 261 which operates and breaks the circuit for relay 263 which, upon deenergizing, closes again the circuit for relay 262. This operation continues until ground is removed from conductor 239 and, as relays 262 and 263 are both slow to fall back, the relay 261 is energized and deenergized at intervals, thus sending out interrupted ground at armatures 212, 219, and 220.

Relay 204, upon deenergizing after the last rotary impulse, completes the following circuit: from interrupted ground, conductor 213, through the resting contact of armature 221 and said armature, working contact of armature 222 and said armature, and stepping magnet 214 of code sending switch E. As soon as ground is sent over this circuit the stepping magnet 214 energizes and when the ground is removed magnet 214 deenergizes. Stepping magnet 214, upon deenergizing, advances the switch wipers 236 and 237 into engagement with the first set of contacts 227 and 228 of their associated banks. Wiper 236 and 237, upon reaching contacts 227 and 228, complete the following circuit: from grounded contact 228 through wiper 237, conductor 206, wiper 236, conductor 240, relay 231, and resistance R to battery. Relay 231 energizes over the above traced circuit and locks itself to ground over grounded conductor 173. When ground comes again over conductor 213 it operates stepping magnet 214 over its previously traced circuit and also operates ringing relay 217 over the following circuit:

from ground over previously traced circuit to armature 222 and thence through the resting contact of armature 215 and said armature, armature 216 and its working contact, and relay 217 to battery. When relay 217 operates, its armature 218 shifts conductor 174 from ground to ground through generator G. Ringing current from generator G flows over conductor 174, through the resting contact of armature 129 and said armature, armature 137 and its working contact, wiper 143, contact 146, line conductor 148, through the stations A'-A²⁰, inclusive, in multiple, and back over line conductor 147, contact 144, wiper 141, working contact of armature 133 and said armature, armature 126 and its resting contact, upper winding of ring cut-off relay 125, conductor 175 and armature 233 and its working contact to ground. All the bells on party line X are operated but relay 125 is not operated, due to its design and adjustment. When ground is removed from conductor 213, relay 217 deenergizes and shifts conductor 174 back to ground and the stepping magnet 214 deenergizes to step the wipers onto the second set of contacts. When ground is again placed on conductor 213 relay 217 operates to connect generator on the called line and the stepping magnet attracts its armature and when the ground is removed from conductor 213 relay 217 shifts its armature from generator to ground and the magnet 214 releases its armature to step the wipers 236 and 237 onto the third set of bank contacts. This process continues until the bells on party line X have been rung four times and the magnet 214 has been deenergized to step the wipers from the fourth to the fifth set of contacts. When the wipers reach the fifth contact set current flows from grounded conductor 206 through wiper 236, the fifth contact in the bank of said wiper, conductor 265, contact 243 in the fifth set on the fourth level of the banks of frequency selector F, wiper 234, and relay 232 to battery. Relay 232 energizes over this circuit and at armature 215 opens the circuit to ringing relay 217. When ground is again placed upon conductor 213 stepping magnet 214 operates as before but obviously relay 217 cannot operate, as its circuit is open at armature 215 and, therefore, the bells on party line X are not rung. However, when stepping magnet 214 deenergizes and steps the wipers 236 and 237 into engagement with the sixth set of contacts relay 232 falls back and reestablishes the circuit for relay 217. When ground is again placed upon conductor 213 the bells on the called line are rung as before. The effect of energizing relay 232 is to cause a time interval or break to occur in the regular periodic rings sent out to the called line so as to distinguish between the first digit

of the code and the second. Now it will be seen that the bells on party line X have been rung four times and after a short interval they have started ringing again. As pointed out, the bells are rung while the wipers are on the sixth set of contacts and they will continue to ring each time the interrupter I places ground on conductor 213 until the eleventh contact set is reached, when the bells will have been rung five more times thus completing the code call 4-5. When the wipers are stepped onto the eleventh contact set current flows from grounded conductor 206 through wiper 236 and the eleventh contact in its associated bank, conductor 266, contact 244 in the bank of the frequency selector F, wiper 235, and resistance R to battery. This circuit shunts the relay 231 and allows it to fall back and when it does so it opens its locking circuit, opens the circuit of ringing relay 217, and at armature 233 places battery on conductor 175 through resistance R'. When the stepping magnet energizes and deenergizes again the wipers 236 and 237 are advanced to the twelfth contact but the bells on the party line X are not rung because the circuit for ringing relay 217 is open and it cannot, therefore, place generator on the line. In case the called subscriber does not respond immediately, the code sending switch E continues to rotate step by step and repeats the code as it passes over the remainder of the contacts, because the first contact is multiplied with the thirteenth, the second with the fourteenth, etc. The switch E will continue to rotate step by step and the proper code will continue to be sent out on the party line X until the called subscriber answers.

If the called subscriber answers at the end of the code the relay 231 will at that time be in deenergized condition and the following circuit for the ring cut-off relay 125 is completed: from ground through resting contact of armature 218 and said armature of relay 217, conductor 174 and over previously traced circuit to substation A' of the called party, through substation A' and back over previously traced circuit to armature 233, and thence through its resting contact to battery through resistance R'. Relay 125 energizes over the above traced direct current circuit, locks itself at armature 127 to grounded conductor 177, extends the called line to the back bridge relay 109, and at armature 128 it disconnects conductor 173 from grounded conductor 177.

As soon as the wipers 236 and 237 are stepped onto either the twelfth or the twenty-fifth contact set in their associated banks, no ground will be present on conductor 206, for the energization of relay 125 removed ground from conductor 173. Relay 205 accordingly deenergizes, removes

ground from starting conductor 239, opens the interrupted ground at armature 222 in case the interrupter I should be operating due to some other call, and closes at armature 226 and its resting contact a point in the release circuit.

Returning now to the connector, when the called line is extended to the back bridge relay 109 the talking circuit is completed. The called subscriber is supplied with talking battery through the windings of the double wound back bridge relay 109. Relay 109 is energized while the receiver at A' remains off the hook and reverses the direction of current flowing in the calling subscriber's battery loop. This operation is of no utility in the present disclosure, but on account of its being a standard operation the circuits are shown in this way.

Conversation may now take place over the established connection and when it is finished both subscribers replace their receivers. The release of the equipment is brought about by the replacement of the receiver at the calling substation A which opens the circuit for the line relay 100 of connector H. The falling back of relay 100 is followed by the deenergization of release relay 101 which removes ground from the release trunk conductor 68 allowing the selector D to release in the well known manner and the switching relay of line switch C to deenergize. The falling back of release relay 101 also completes the following release circuit for connector H and frequency selector F: from ground through armature 120' and its resting contact, armature 122 and its resting contact, conductor 171, resting contact of armature 226 and said armature, conductor 172, and in multiple through off normal springs 208 and 207 and release magnet 221 of frequency selector F to battery, and off normal springs 107 and 108 and release magnet 190 of connector H to battery. The release magnets 190 and 221 energize over the above traced circuit and restore their respective switches to normal.

In the foregoing it is shown how a connection with party line 123 is established and the code call 45 is sent out. We will assume that the same subscriber calls another subscriber (for example) A²⁰ on the same party line and whose code number we will assume is 22.

In this case the calling subscriber will remove his receiver and dial 123 as before. At the end of the third digit the impulsive circuit is switched to the frequency selector as in the preceding call. In the same manner as before described the vertical magnet 201 raises the shaft and wipers in response to the fourth digit which in this case is 2. Likewise the rotary magnet 203 operates as before and rotates the wipers in response to the final digit which in this

case is 2 also. We now have the wipers of the connector switch on the terminals of the party line X as in the preceding example and we also have the wipers of the frequency selector F on the second set of contacts in the second level of the banks of said selector. After the end of the last digit the slow acting relay 204 falls back and completes the circuit from interrupted ground to the stepping magnet 214 of the code switch E as before.

The ringing relay 217 is now operated while the wipers 236 and 237 are on the first two contact sets or on the thirteenth and fourteenth, depending upon whether the code ringing switch E started this time from the 12th or the 25th set of contacts, however, we will assume that it started from the twenty-fifth set in which case the bells on party line X will, as stated, be rung while the wipers are on the first two sets of contacts, but when the wipers 236 and 237 reach the third contact set current flows from grounded conductor 206 through wiper 236 and the third contact in its associated bank, conductor 242, bank contact 245, wiper 234, and relay 232 to battery. Relay 232 energizes and remains energized until the wiper 236 passes off the third contact. Relay 232, while energized, holds open the circuit to ringing relay 217 and, therefore, no ringing takes place while wiper 236 is on the third contact and a space is produced between the first and second digits of the code. The bells on party line X will be rung again when the fourth contact set is reached and also on the fifth but when the sixth contact set is reached wiper 236 allows current to pass from grounded conductor 206, through wiper 236 and the sixth contact in its associated bank, conductor 247, bank contact 246, wiper 235, and resistance R to battery. This circuit shunts relay 231 and allows it to fall back and open the circuit for ringing relay 217 at armature 216. If the called subscriber does not answer, the further rotation of switch E will reenergize relay 231 when the wiper 236 reaches the thirteenth contact in its associated bank, and the code will be repeated over and over until the called subscriber answers or the calling subscriber hangs up. If the called subscriber answers the ringing is stopped at the end of the code, the connection is completed, communication takes place and release is effected all in the same way as in the previous example.

It could be shown how every one of the twenty code combinations is sent out, but it is thought that with the explanation already given, an examination of the drawing (Fig. 3) will clearly show how any code may be sent out on any party line that appears in the banks of connector H. In case a smaller number of codes are required, con-

tact sets in the bank of the code selecting switch F which are not used are not wired to the bank of the ringing switch E, but are left dead except for the upper contacts of such contact sets, which are connected to ground as shown in the case of the contact sets in the fifth level and the last five contact sets in levels 1 to 4. With this arrangement, if a subscriber should call an unused code number, by accident or otherwise, relay 232 will energize at once and no signaling will take place.

In code ringing party line systems known heretofore, the called subscriber can, by answering during the time that the code is being sent out, cause the code to stop before it is finished, thereby signalling the wrong subscriber. However, in the present invention this difficulty is done away with in a very simple manner. As previously pointed out, during the time that the relay 231 of frequency selector F is energized, the return path of the generator is connected to ground at armature 233. Ring cut-off relay 125 of the connector H, included in the circuit for ringing current, can energize only when direct current flows through it and, since relay 231 does not deenergize until the end of the code, no direct current can flow through the circuit during the code and the ring cut-off relay cannot energize to break the ringing circuit. As before pointed out, the deenergization of relay 231 ends the last digit of the code and upon deenergizing, it connects battery at armature 233 through resistance R' to the circuit so that should the called subscriber have his receiver off the hook or if he removes it before relay 231 energizes again to repeat the code, direct current flows over the circuit previously traced for relay 125 which energizes and completes the talking circuit in a manner already explained. The code ringing switch E, however, does not stop as soon as the called party answers but continues to advance step by step until the wipers reach one of their normal positions. In actual practice, however, most if not all of the bells on the party line are stopped from ringing or are caused to give only a low buzz, due to being shunted, whenever a called subscriber takes off his receiver during the code series. To overcome this, each and every subscriber on the party line is definitely instructed not to answer during the code and in case one of them forgets, the unpleasant ring in the ear is a reminder that he has committed an error. Accordingly, very soon all of the subscribers form the habit of not answering until the code is finished.

If the called subscriber does not respond, the calling subscriber will hang up and he is likely to do so while the code is being sent out. If the code should be stopped immedi-

ately when the calling subscriber hangs up, many times the last code would be that of some other subscriber and not the one that is wanted. In the present disclosure, however, the code will be completed even though the calling subscriber does hang up his receiver before its completion. Upon referring to the drawings, it will be seen that neither the connector H nor the frequency selector F can release and that code sending switch E cannot stop until relay 205 of selector E deenergizes. Now when the calling subscriber hangs up and allows relays 100 and 101 to deenergize ground is removed from conductor 173 at armature 123, but ground is kept on conductor 173 from wiper 237, over conductor 206, working contact of armature 228 and said armature. This ground holds relays 125, 117, and 205 energized until the wipers of switch E reach the twelfth or twenty-fifth contact set. When they do so the code has been finished, ground is no longer present on them, relay 205 deenergizes, and switches F and H release in the usual manner.

Having described our invention, what we consider to be new and desire to have protected by Letters Patent will be pointed out in the appended claims.

What we claim as our invention is:

1. In a telephone system, a party line, a plurality of signals on said line, a source of ringing current, means for connecting said source of current to the line so as to operate said signals according to predetermined codes, means for disconnecting said source of current from said line, and means for rendering said disconnecting means inoperative except at the end of the code. 95

2. In a telephone system, a party line, a plurality of signals on said line, a source of ringing current, means including subscriber controlled automatic switches for connecting said current source to said line so as to operate said signals according to a predetermined code, means for disconnecting said source of current from the line, and means for rendering said last means ineffective until the code is finished. 105

3. In a telephone system, a calling and a called line, a plurality of stations on the called line, an automatic connector switch for connecting said lines, a code selecting switch and cooperating mechanism associated with said connector for signalling any station on said called line according to a pre-assigned code ring, and means for preventing the release of said connector in case the calling subscriber hangs up his receiver before the code ring is completed. 115

4. In a telephone system, a calling and a called line, a plurality of stations on the called line, an automatic connector switch for connecting said lines, a code selecting switch and cooperating mechanism associat- 125

ed with said connector for signalling any station on said called line according to a pre-assigned code ring, means for releasing said connector controlled by the calling subscriber, and means for preventing the calling subscriber from producing a false signal by releasing said connector before the code ring is completed.

5. In a telephone system, a calling and a called line, a plurality of stations on the called line, an automatic connector switch for connecting said lines, a code selecting switch and cooperating mechanism associated with said connector for signalling any station on said called line according to a pre-assigned code ring, means in said connector for releasing the same when the calling man hangs up his receiver, and means in said code selecting switch for preventing the operation of said releasing means before the code ring is completed.

6. In a telephone system, a calling and a called line, a plurality of stations on the called line, an automatic connector switch for connecting said lines, a code selecting switch and cooperating mechanism associated with said connector for signalling any station on said called line according to a pre-assigned code ring, means in said connector for releasing the same when the calling man hangs up his receiver, a third switch included in the said mechanism cooperating with said code selector, and means for preventing the operation of said releasing means when the said third switch is out of its normal position.

7. In a telephone system, a calling and a called line, a plurality of stations on the called line, an automatic connector switch for connecting said lines, a code selecting switch and cooperating mechanism associated with said connector for signalling any station on said called line according to a pre-assigned code ring, and means for preventing the called subscriber from stopping the signalling operation before the code ring is completed.

8. In a telephone system, a calling and a called line, a plurality of stations on the called line, an automatic connector switch for connecting said lines, a code selecting switch and cooperating mechanism associated with said connector for signalling any station on said called line according to a pre-assigned code ring, means for terminating the signalling operation when the called subscriber answers, and means for preventing the called subscriber from producing a false signal by answering before the code ring is completed.

9. In a telephone system, a calling and a called line, a plurality of stations on the called line, an automatic connector switch for connecting said lines, a code selecting switch and cooperating mechanism asso-

ciated with said connector for signalling any station on said called line according to a pre-assigned code ring, means for repeating the code ring at intervals, means for terminating the signalling operation when the 70 called subscriber answers, and means for insuring that any code ring which is started will be completed whether the called subscriber answers or not.

10. In a telephone system, a calling and 75 a called line, a plurality of stations on the called line, an automatic connector switch for connecting said lines, a code selecting switch and cooperating mechanism associated with said connector for signalling 80 any station on said called line according to a pre-assigned code ring, a ring cut-off relay in said connector connected in series with the called line during the signalling operation and adapted to stop the ringing 85 when the called subscriber answers, and means whereby said relay is rendered ineffective until after the code ring has been completed.

11. The combination, with an automatic 90 progressively movable connector switch for completing connections to called subscribers' lines, of a progressively movable code ringing switch, and a release magnet for said connector switch controlled by said ringing 95 switch.

12. The combination, with an automatic progressively movable connector switch for completing connections to called subscribers' 100 lines, of a progressively movable code ringing switch, a line relay for said connector, and a release magnet for said connector controlled jointly by said line relay and said ringing switch.

13. The combination, with an automatic 105 progressively movable connector switch for completing connections to called subscribers' lines, of a progressively movable code ringing switch, a line relay for said connector switch, a second relay energized while said ringing switch is operating to transmit a code ring, and a release magnet for said connector controlled jointly by said relays.

14. The combination with an automatic connector switch for completing connections 115 to subscribers' lines, of code ringing equipment for signaling on a connected line, said equipment comprising a code selecting switch and a code sending device, means for restoring said connector, and means for preventing the restoration of said connector while said sending device is transmitting a code.

15. The combination, with an automatic connector switch for completing connections 125 to subscribers' lines, of code ringing equipment for signaling on a connected line, said equipment comprising a code selecting switch and a code sending device, ring cut-off means in said connector adapted to be 130

- controlled by a called subscriber for stopping the transmission of code signals over his line, and means for rendering said ring cut off means ineffective while said sending device is transmitting a code.
16. The combination, with an automatic progressively movable switch for completing connections to subscribers' lines, of a progressively movable code ringing switch for signaling over a connected line, a ring cut-off relay in said connector, and means for preventing the operation of said relay while said ringing switch is operating to transmit a code ring.
17. The combination, with an automatic progressively movable connector switch for completing connections to subscribers' lines, of a progressively movable code ringing switch for signaling over a connected line, a relay energized during the operating of said ringing switch, a ring cut-off relay in said connector, and an energizing circuit for said ring cut off relay completed only when said first relay is deenergized.
18. In a telephone system, a calling and a called line, a plurality of stations on the called line, an automatic connector switch for connecting said lines, code ringing mechanism associated with said connector for signalling any station on the said called line according to a pre-assigned code ring,

and means for preventing the release of said connector in case the calling subscriber hangs up his receiver before the code ring is completed.

19. In a telephone system, a calling and a called line, a plurality of stations on the called line, an automatic connector switch for connecting said lines, code ringing mechanism associated with said connector for signaling any station on the said called line according to a pre-assigned code ring, means for releasing said connector controlled by the calling subscriber, and means for preventing the calling subscriber from producing a false signal by releasing said connector before the code ring is completed.

20. In a telephone system, a calling and a called line, a plurality of stations on the called line, an automatic connector switch for connecting said lines, code ringing mechanism associated with said connector for signalling any station on said called line according to a pre-assigned code ring, and means for preventing the called subscriber from stopping the signalling operation before the code ring is completed.

Signed by us at Chicago, Cook County, Illinois, this 22d day of Nov., 1920.

BERNARD D. WILLIS.
